UNITED STATES PATENT OFFICE.

OTTO METZNER, OF CINCINNATI, OHIO, ASSIGNOR TO THE ROCKWOOD POTTERY COMPANY, OF CINCINNATI, OHIO, A CORPORATION OF OHIO.

DESIGN FOR A GAS-HEATER.

52,514.

Specification for Design.

Patented Oct. 1, 1918.

Application filed June 10, 1918. Serial No. 239,332. Term of patent 7 years.

To all whom it may concern:

Be it known that I, OTTO METZNER, a citizen of the United States, and a resident of Cincinnati, in the county of Hamilton and State of Ohio, have invented a new, original, and ornamental Design for Gas-Heaters, of which the following is a specification, reference being had to the accompanying drawing, forming part thereof.

Figure 1 is a perspective view of a gas heater showing my new design.

Fig. 2 is a vertical cross section of same.
I claim:

The ornamental design for a gas heater, as shown.

OTTO METZNER.
